US00D618239S

(12) United States Design Patent
Chen et al.

(10) Patent No.: US D618,239 S
(45) Date of Patent:  Jun. 22, 2010

(54) THIN CLIENT

(75) Inventors: Yun-Lung Chen, Taipei Hsien (TW);
Hong-Jin Wu, Shenzhen (CN); Jian Huang, Shenzhen (CN)

(73) Assignee: Hon Hai Precision Industry Co., Ltd.,
Tu-Cheng, Taipei Hsien (TW)

() Term: 14 Years

(21) Appl. No.: 29/340,643

(22) Filed: Jul. 22, 2009

(51) LOC (9) Cl. 14-02

(52) U.S. Cl. D14/356

(58) Field of Classification Search D14/137,
D14/167, 168, 218, 231, 233, 235, 237, 240-242,
D14/299, 432, 435, 436, 155, 496, 300, 301,

(57) CLAIM

The ornamental design for a thin client, as shown and described.

DESCRIPTION

FIG. 1 is a perspective view of the thin client showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the figures are for the purpose of illustrating unclaimed portions of the thin client and form no part thereof.

1 Claim, 7 Drawing Sheets
